Inventor:

Cesphas B. Rogers,
By his Attorney, Leo F. McNeely

UNITED STATES PATENT OFFICE.

CEPHAS B. ROGERS, OF DANBURY, CONNECTICUT.

DESIGN FOR AN ELECTRIC LIGHT BRACKET.

Application filed March 31, 1923. Serial No. 5,657. Term of patent 3½ years.

To all whom it may concern:

Be it known that I, CEPHAS B. ROGERS, a citizen of the United States, residing at Danbury, county of Fairfield, and State of Connecticut, have invented a new, original, and ornamental Design for Electric Light Brackets, of which the following is a specification, reference being had to the accompanying drawing, forming part thereof.

In the accompanying drawings,
Fig. 1, is a front elevation;

Fig. 2, is a side elevation; and
Fig. 3, a rear elevation, of an electric light bracket, showing my new design.

I claim:

The ornamental design for an electric light bracket, as shown.

CEPHAS B. ROGERS.
